[57] CLAIM

The ornamental design for a foot ornament, substantially as shown and described.

DESCRIPTION

FIG. 1 is a left front perspective view of a foot ornament showing my new design, the broken lines being environmental and forming no part of the claimed design;

FIG. 2 is a left side elevational view thereof;

FIG. 3 is a right side elevational view thereof;

FIG. 4 is a top plan view thereof;

FIG. 5 is a front perspective view thereof;

FIG. 6 is a rear perspective view thereof.
